Des. 209,036

Patented Oct. 31, 1967

209,036

DISPOSABLE PROTECTIVE SHOE COVER

Harold Zimmon, Los Altos Hills, Calif. (% Zimmon & Co., Inc., 215 O'Neill Ave., Belmont, Calif. 94002)

Filed Apr. 18, 1966, Ser. No. 1,911

Term of patent 14 years

(Cl. D2—271)

FIG. 1 is a side elevational view of my protective shoe cover in flat position.

FIG. 2 is a view similar to FIG. 1 from the opposite side.

FIG. 3 is a top plan view of the cover in wearing position.

FIG. 4 is a side elevational view of the protective shoe cover on a reduced scale in a wearing position, the broken line showing of a portion of a sock and leg being for purposes of illustration only.

I claim:

The ornamental design for a disposable protective shoe cover, as shown and described.
